E. A. OLLEY.

PANEL BOARD AND LINING STRIP SUPPORTING MEANS.

APPLICATION FILED JUNE 14, 1913.

1,225,997.

Patented May 15, 1917.

UNITED STATES PATENT OFFICE.

EDWIN A. OLLEY, OF SYRACUSE, NEW YORK, ASSIGNOR TO CROUSE-HINDS COMPANY,
OF SYRACUSE, NEW YORK, A CORPORATION OF NEW YORK.

PANEL-BOARD AND LINING-STRIP SUPPORTING MEANS.

1,225,997.

Specification of Letters Patent.

Patented May 15, 1917.

Application filed June 14, 1913. Serial No. 773,747.

To all whom it may concern:

Be it known that I, EDWIN A. OLLEY, a citizen of the United States, and a resident of Syracuse, in the county of Onondaga and 5 State of New York, have invented a certain new and useful Panel-Board and Lining-Strip Supporting Means, of which the following is a specification.

This invention relates to panel board cabin- 10 nets and particularly to means for supporting the panel board and the lining strips in the cabinet, and the invention consists in the novel features of construction hereinafter set forth and claimed.

15 In describing this invention reference is had to the accompanying drawings in which like characters designate corresponding parts in all the views.

Figure 1 is a plan view of this means for 20 supporting the panel board and lining strips, contiguous portions of the lining strips being shown.

Fig. 2 is a sectional view on line "A—A" 25 Fig. 1, the lining strips being omitted.

Fig. 3 is a sectional view on line "B—B" 30 Fig. 2, parts being removed and the lining strips being shown.

Fig. 4 is a vertical sectional view on line 35 "C—C" Fig. 2, the panel board and one of the lining strips being shown.

The means for supporting the panel board and the lining strips is usually arranged at a corner of the panel board and is known commercially as a corner iron, and for convenience, will be referred to throughout the specification as a corner iron.

This corner iron comprises a supporting bracket designed to be secured to the wall or to the bottom of the panel board cabinet, 40 and means detachably carried by the standard for holding the panel board, as clamping means including members having upper and lower jaws for engaging the opposite faces of the panel board, the corner iron also including means for gripping the lining strips, and parts being preferably so formed that they can be struck up out of sheet metal.

The bracket includes a base flange 1 and a standard 2 projecting from the base flange, 50 the base flange being formed with comparatively large openings 3 through which fastening members as screws 4 are passed into the wall or bottom of the cabinet A, the heads of the screws 4 bearing against wash-

ers 5 large enough to cover the holes in any 55 position the screws may occupy relatively to the side walls of the holes 3. The base flange 1 is elongated and from one of the long sides thereof the standard 2 rises in a direction at a right angle to the flange 1, the 60 major part of the standard 2 being flat and the side margins 6 thereof being bent into an angular position relatively to the major part of the standard into position to engage the outer sides of the lining strips 7 which 65 usually extend in planes at a right angle to each other.

The standard 2 is also formed with a centrally located slot 8 near the base flange 1 for receiving the corner of the panel board 70 9, Fig. 4. 10 and 11 are the clamping members having jaws 12 and 13 for engaging respectively the lower and upper faces of the panel board 9, the members 10 and 11 being formed of sheet metal and the member 10 75 having its body portion extended upwardly between the body of the member 11 and the standard 2 and being adjustable vertically in a guide way formed in the standard 2. The body of the member 10 is formed with 80 an opening 14 alined with the slot 8. The guide way is preferably formed by inwardly bent lugs 15 struck from the body portion of the standard 2 on opposite sides of the median line thereof, these lugs being bent to 85 extend in a direction parallel to the marginal flanges 6 of the standard into positions to engage the end edges of the strips 7.

The member 10 is formed with its body portion substantially flat and with its side 90 margins 16 bent into angular relation to its intermediate portion to conform the guide way and to engage the inner faces of the ears 15. Said margins 16 engage the side edges of the panel board. The edges of the 95 margin 16 also engage the end edges of the strips 7. The member 10 is formed with a rearwardly extending threaded stud 17 extending through a central longitudinal slot 18 in the major part of the standard 2 and 100 a wing nut 19 turns on the stud 17 against the rear faces of the standard 2 to hold the jaw member 10 at any elevation.

The member 11 is formed of sheet metal and is arranged to extend in a straight line 105 across the corner portion of the panel board 9 with its lower edge or jaw 13 opposed to the jaw 12 of the member 10; and the side

edges 20 of the member 11 are arranged in a position opposed to the marginal flanges 6 of the standard 2 to coöperate with said marginal flanges to grip the lining strips 7. The intermediate part of the member 11 is spaced apart from the lining strips, Fig. 3. The upper end of the member 11 is provided with a rearwardly turned flange 21 which forms a cover for the space between the members 10 and 11 and also a stop for limiting the downward movement of the member 11. The member 11 is secured in position relatively to the standard 2 and member 10 by clamping means consisting of a stud or screw 22 extending through aligned slots 18 and 23 in the standard and in the body of the clamping member 10, and a wing nut 24 turning on the stud 22.

In operation there is a corner iron at each corner of the panel board and each bracket is adjustable into position owing to the enlarged holes 3, and the members 10, 11 are adjusted vertically to various heights to support the panel board with its face in a vertical plane, the corners of the panel board extending through the slots 8 and 14 of the standard 2 and member 10. The lining strips are then placed in position and the clamping member 11 clamped in position with its jaw 13 engaging the upper edge of the panel board.

What I claim is:—

1. A device of the character described including a bracket comprising a standard formed with an opening for receiving the corner of the panel board, and means adjustably carried by the standard for holding the panel board, substantially as and for the purpose set forth.

2. A device of the character described including a bracket comprising a standard, the major part of the standard being flat and formed with an opening for receiving a corner of the panel board, and means carried by the standard for holding the panel board, substantially as and for the purpose described.

3. A device of the character described comprising a bracket including a standard, the major part of which is flat, the standard being formed with angularly arranged margins and the flat portion being formed with an opening for receiving the corner of the panel board, and also with a vertical guide, means for holding the panel board at the corner including a member arranged in the guide, and means for securing said member to the standard, substantially as and for the purpose specified.

4. A device of the character described including a bracket comprising a flat portion having an opening for receiving the corner of the panel board, and means for holding the panel board engaging the upper and lower sides thereof, and means for securing

the holding means to the flat part of the standard, substantially as and for the purpose set forth.

5. A device of the character described including a bracket comprising a base flange and a standard bent upwardly from the base flange, the major part of the standard being flat and formed with a centrally located opening near the base flange for receiving the corner of the panel board, and clamping means carried by the standard for engaging the panel board, substantially as and for the purpose described.

6. A device of the character described comprising a bracket including a base and a standard extending upwardly from the base, the major part of the standard being flat and having an opening for receiving the corner of the panel board and the margins thereof being bent into angular relation to said major part, and clamping means including two members adjustably carried by the standard and having upper and lower jaws for engaging the upper and lower faces of the panel board, the lower jaw member having a flat upwardly extending body portion engaging the flat portion of the standard, substantially as and for the purpose specified.

7. A device of the character described comprising a bracket including a base and a standard extending upwardly from the base, the major part of the standard being flat and having an opening for receiving the corner of the panel board and the margins thereof being bent into angular relation to said major part, and clamping means including two members adjustably carried by the standard and having upper and lower jaws for engaging the upper and lower faces of the panel board, the lower jaw member having a flat upwardly extending body portion engaging the flat portion of the standard and margins extended at an angle to said body portion in position to engage adjoining side edges of the panel board, substantially as and for the purpose set forth.

8. A device of the character described comprising a bracket including a base and a standard extending upwardly from the base, the major part of the standard being flat and having an opening for receiving the corner of the panel board and the margins thereof bent into angular relation to said major part into position to engage the outer faces of the lining strips, and clamping means including two members carried by the standard and having upper and lower jaws for engaging the upper and lower faces of the panel board, the lower jaw member having a flat upwardly extending body portion engaging the flat portion of the standard and margins extended at an angle to said body portion in position to engage adjoining side edges of the panel

board, and the upper jaw member having its side edges arranged to engage the inner face of the lining strips and clamping the same toward the margins of the standard and means for securing the clamping members to the standard, substantially as and for the purpose described.

9. A device of the character described including a bracket comprising a base and a standard extending upwardly from the base, the major part of the standard being flat and formed with a centrally located opening near the base for receiving the corner of the panel board, and clamping means including two members carried by the standard and having upper and lower jaws for engaging respectively the upper and lower faces of the panel board, the lower jaw member having an upwardly extending body formed with a slot alined with the slot of the standard and being interposed between the standard and the upper jaw member, substantially as and for the purpose specified.

25 10. A device of the character described including a bracket comprising a base and a standard extending upwardly from the base, the major part of the standard being flat and formed with a centrally located opening near the base for receiving the corner of the panel board, and clamping means including two members carried by the standard and having upper and lower jaws for engaging respectively the upper and lower faces of the panel board, the lower jaw member having an upwardly extending body formed with a slot alined with the slot of the standard and being interposed between the standard and the upper jaw member, and the lower jaw member extending across the corner of the panel board, substantially as and for the purpose set forth.

11. A device of the character described including a bracket comprising a base and a standard extending upwardly from the base, the major part of the standard being flat and formed with a centrally located opening near the base for receiving the corner of the panel board, and clamping means including two members carried by the standard and having upper and lower jaws for engaging respectively the upper and lower faces of the panel board, the lower jaw member having an upwardly extending body formed with a slot alined with the slot of the standard and being interposed between the standard and the upper jaw member, and the standard having its margins bent into angular relation to the major part thereof, the upper jaw member having its side edges arranged opposite said margins to coöperate therewith to grip the lining strips, substantially as and for the purpose described.

12. A device of the character described including a bracket comprising a base and a standard extending upwardly from the base, the major part of the standard being flat and formed with a centrally located opening near the base for receiving the corner of the panel board, and clamping means including two members carried by the standard and having upper and lower jaws for engaging respectively the upper and lower faces of the panel board, the lower jaw member having an upwardly extending body formed with a slot alined with the slot of the standard and being interposed between the standard and the upper jaw member, and the standard having its margins bent into angular relation to the major part thereof, the upper jaw member having its side edges arranged opposite said margins to coöperate therewith to grip the lining strips, and its intermediate portion extending across the corner of the panel board and spaced apart from the lining strips, substantially as and for the purpose specified.

13. A device of the character described comprising a sheet metal bracket including a base flange and a standard bent upwardly from the base flange, the major part of the standard being flat, the side margins of the standard being bent into angular relation to the major part of the standard to engage the outer faces of the lining strips, the major part of the standard being formed with inwardly bent lugs extending in a position substantially parallel to the side margins, the lugs forming a guide way, and clamping means including two members carried by the standard and adjustable lengthwise thereof, the members having respectively upper and lower jaws for engaging opposite faces of the panel board, the lower jaw member having its body portion extending into the guide way and fitting the same and having its side margins bent to conform to the lugs, the upper jaw member having its side edges opposed to the side margins of the standard, and means for adjustably clamping the jaw members to the standard, substantially as and for the purpose specified.

14. A device of the character described comprising a sheet metal bracket including a base flange, and a standard bent upwardly from the base flange, the major part of the standard being flat and formed with a centrally located opening near the base flange for receiving the corner of the panel board, the side margins of the standard being bent into angular relation to the major part of the standard to engage the outer faces of the lining strips, the major part of the standard being formed with inwardly bent lugs extending in a position substantially parallel to the side margins, the lugs forming a guide way, and clamping means in-

cluding two members carried by the standard and adjustable lengthwise thereof, the members having respectively upper and lower jaws for engaging opposite sides of the panel board, the lower jaw member having its body portion extending into the guide way and fitting the same and having its side margins bent to conform to the lugs, said body portion of the lower jaw member also being formed with a slot alined with the slot of the standard, the upper jaw member having its side edges opposed to the side margins of the standard, and means for adjustably clamping the jaw members to the standard, substantially as and for the purpose set forth.

15. The combination of a panel board, and a corner iron including a bracket having a standard flat in general outline and formed with a central opening therein for receiving the corner of the panel board, and a clamping member carried by the standard and coacting with the panel board.

In testimony whereof, I have hereunto signed my name, in the presence of two attesting witnesses, at Syracuse, in the county of Onondaga, in the State of New York, this 11th day of June, 1913.

EDWIN A. OLLEY.
